UNITED STATES PATENT OFFICE.

JOHN C. CORAM, OF LOWELL, MASSACHUSETTS.

MACHINE FOR FINISHING TUBES.

SPECIFICATION forming part of Letters Patent No. 426,526, dated April 29, 1890.

Application filed September 4, 1889. Serial No. 322,942. (No model.)

To all whom it may concern:

Be it known that I, JOHN C. CORAM, a subject of Victoria, Queen of the United Kingdom of Great Britain and Ireland, residing in Lowell, in the county of Middlesex and Commonwealth of Massachusetts, have invented a new and useful Improvement in Machines for Trimming Tubes, of which the following is a specification.

10 My invention relates to machines for trimming tubes; and it consists in means for placing the tubes upon the mandrels, means for presenting the tubes carried on said mandrels to the action of cutters, means for carrying the 15 mandrels away from the cutters after the tubes are trimmed, means for burnishing the tubes, and means for removing the tubes from the mandrels.

In the accompanying drawings, on three 20 sheets, Figure 1 is a front elevation of a machine embodying my improvement, some of the concealed parts being shown in dotted lines, the lower parts of the frame, slide-operating lever, and connecting-rod being 25 broken away; Fig. 2, a right end elevation of said machine, the lower parts of the supporting-frame of said machine being broken away; Fig. 3, a front elevation of the lower part of the 30 frame; Fig. 4, a section on the line 4-4 in Fig. 1; Fig. 5, a rear elevation of the slide-operating cam; Fig. 6, a front elevation of the cam which moves the cutter-shaft and cutters into 35 position for operating on the tubes; Fig. 7, a front elevation of the dog-plate.

A is the bed of the machine, supported upon suitable legs and supporting the operative parts of the machine. From any suitable overhead-shaft (not shown) are driven by open 40 belts the cutter-shaft C and the mandrel-rotating sleeve D, the belts running on the grooved pulleys d, fast on said cutter-shaft and mandrel-rotating sleeve, respectively. From the same overhead shaft is driven the 45 cam-shaft E by a quarter-turn belt running on the fast pulley e on said cam-shaft, e' being a loose pulley on said cam-shaft. The cam E', fast on the cam-shaft, is provided with a cam-groove e², which receives a stud e³, projecting forward from the connecting-rod e⁴, said rod having a longitudinal slot e⁵, which receives the cam-shaft and guides said rod.

The rod e⁴ is jointed at e⁶ at its lower end to the free end of the lower arm e⁷ of the bell-crank e⁸, said bell-crank being pivoted at e⁹ 55 on the frame of the machine, and the other end of said bell-crank e⁸ is pivoted to one end of the nearly-horizontal connecting-rod e¹⁰, the other end of said last-named rod being adjustably pivoted to the slide E² by well-known 60 means. The main body of the slide E² moves in V-shaped ways a² a³ on the frame or bed A, the upper ways a² consisting of two blocks vertically adjustable by means of the screws a⁴, turning in ears a⁵ on said bed and held in 65 place by cap-screws a⁶, which pass through vertical slots a⁷ in said movable blocks a² into said frame. The rotation of the cam-shaft E and cam E' gives the slide E² a reciprocating motion in its ways. 70

Secured to the upwardly-projecting part e¹¹ of the slide E² is a feed-block e¹², the same being adjustable endwise on said slide by means of slots e¹³ in the slide and bolts e¹⁴, which pass through said slots into said block, 75 as shown in Fig. 1, and supported on said feed-block is a feeder e¹⁵, the same being a trough e¹⁶, in which the tubes are laid, said trough being provided with a reduced shank e¹⁷, which passes through an ear e¹⁸ on said feed-block and is surrounded by a spiral spring e¹⁹, compressed between said ear e¹⁷ and said trough, the trough proper being supported by a stud or bolt e²⁰, inserted in the side thereof and projecting through a horizontal slot e²¹ in another ear e²² on said block. The amount of compression of the spring e¹⁹ is varied by turning the nut e²³ and check-nut e²⁴ on the end of the shank e¹⁷ outside of the ear e¹⁷. The tube, if tapering, is laid in 80 the trough e¹⁶ with its large end toward the mandrels d², and the movement of the slide to the left in Fig. 1 forces the tube onto that one of said mandrels which at the time is the front upper mandrel, there being four mandrels arranged parallel with the horizontal shaft D' and journaled at equal intervals on the disk d², secured to said shaft. The mandrels are given a constant rotation by pinions d³, secured to said mandrels concentrically 85 therewith, engaging a gear D², fast on the sleeve D, said sleeve being rotated, as above described. To the shaft D', concentrically therewith, is secured a plate d⁴, having as 90 95 100

many radial slots d^5 as there are mandrels, and between said slots having straight faces d^6 . On the cam-shaft E is secured a dog-plate D³, (see Figs. 4 and 7,) the side of which rests 5 during the greater part of the revolution of said dog-plate against one of the straight faces d^6 of the plate d^4 and prevents the rotation of said last-named plate, one of the mandrels at this time being in position to receive a tube from the trough e^{16} . A projection d^7 , secured to the side of the dog-plate and offset therefrom, as shown in Fig. 4, once in every revolution of the dog-plate enters one of the slots of the plate d^4 and rotates the last-named plate one-fourth of a revolution, the face of the dog-plate being cut away in advance and in the rear of the projection d^7 at d^8 for a sufficient distance to allow the parts of the plate d^4 to pass said dog-plate. A quarter-revolution of the plate d^4 brings the mandrel which receives the first tube into a position near to the trimming-cutters C' C², the same being sharp-edged steel disks fast on the cutter-shaft C, above named. 20 The cutter-shaft is parallel with the shaft D', and is journaled in arms c c, radially secured to the shaft C³, the latter being journaled in the frame of the machine or in brackets c', secured to said frame. Another arm c² is 25 secured to the shaft C³, and its rear free end or an anti-friction roller c³ carried thereon is held by a spring c⁴ (secured to one of said brackets c' and pressing upon said arms c²) in contact with the periphery of a cam C⁴, 30 fast upon the cam-shaft E, (see Figs. 4 and 6,) so that at every revolution of the shaft E the cutters are thrown down by raising the rear end of the arm c² and the rocking of the shaft C³ against the tube on the (for the time being) 35 rear upper mandrel d⁹ and trim off the ends of said tube and reduce the tube to a definite length equal to the distance between the cutters C' C². After the tubes are trimmed the pressure of the spring c⁴ rocks the shaft C³ in 40 the other direction and raises the cutters, the radius of the cam being suddenly reduced at c⁵ to allow the arm c² to drop just before the projection d⁷ on the dog-plate turns the plate d⁴ another quarter of a revolution. In the 45 meantime another tube has been placed on the then front upper mandrel. The second quarter-revolution of the plate d⁴ carries the trimmed tube to the burnishing devices. 50

The burnishing devices (see Fig. 1) consist 55 of a horizontal shaft F, journaled in the frame of the machine and having a longitudinal motion therein, and driven from the same overhead shaft from which the mandrel-rotating sleeve and cutter-shaft are driven by 60 a belt or band connecting said overhead shaft and a pulley f, fast on the shaft F, said shaft having a conical hole f' at its inner end capable of receiving the free end of a mandrel and tube, and having also a collar f², provided 65 with annular groove f³, which receives the forked upper end of a bell-crank lever f⁴, pivoted at f⁵ on the frame of the machine,

the lower end of said lever being provided with an anti-friction roller f⁶, which rests upon an incline f⁷, secured to the slide E², and is held in contact therewith by the contractile force of a spring f⁸, connected to the lower arm of said lever and to the bed of the machine, so that when the slide E² moves in the direction necessary to push a tube upon the mandrel the incline f⁷ moves out from under the lower arm of said lever and allows the lever f⁴ to be turned by the spring f⁸ in a direction to throw the shaft F to the left in Fig. 1 and force its hollow end over the lower 75 rear mandrel and against the end of the tube, thus burnishing the end of said tube by friction, said shaft F and mandrel revolving in opposite directions at considerable speeds. When the slide E² returns to position, the 80 incline f⁷ runs under the lower end of the lever f and draws the burnishing-shaft F away from the mandrel at the same time that the cutters C' C² are thrown upward and backward by the action of the spring c⁴. The 85 next quarter-revolution of the plate d⁴ carries the tube first placed upon a mandrel forward, the mandrel which carries said tube being the front lower mandrel. Another movement of the slide now places a tube upon the 90 fourth mandrel, and at the same movement of the slide the strippers G G, secured to the slide, are carried over the lower front mandrel. The strippers G G are nearly- vertical springs secured to the slide E², and provided at their upper ends with jaws g g, the inner faces of which are provided with rounded grooves g' g', adapted to surround the mandrel back of the tube, said jaws being held apart in passing over the mandrel by the 95 head g² of the spring-bolt G', arranged to slide in a bracket g³ on said slide E², said head g² being held between said jaws by a spiral spring g⁴ and a nut g⁵, carried on said bolt near its free end, until by the movement 100 of said slide said bolt is carried against a bracket g⁶, supported on said bed, which pushes said head-gear g² out from between said jaws and allows them to close upon the mandrel, so that the said slide in returning 105 to position strips the tube from the mandrel. The jaws in their return motion are opened for another operation by running on opposite sides of a wedge-shaped piece g⁷, supported on a bracket g⁸, secured to the frame of the 110 machine, until the head g² is forced by the spring g⁴ between said jaws. 115

Obviously the number of mandrels may be increased or diminished, as desired. Thus the tubes may be trimmed without burnishing, which would require but three mandrels, or the number of mandrels may be doubled, and the feeding, trimming, burnishing, and stripping devices may be duplicated. 125

I claim as my invention—

1. The combination of a mandrel, means, substantially as described, for rotating the same, cutters, and means, substantially as described, for rotating the same against said

mandrel to trim the ends of a tube placed upon said mandrel, as and for the purpose specified.

2. The combination of the sliding feed-trough to carry a tube placed therein, a mandrel to receive said tube, and a rotary cutter to trim said tube on said mandrel, as and for the purpose specified.

3. The combination of the sliding feed-trough to carry a tube placed therein, a mandrel to receive said tube, and rotary cutters to trim said tube on said mandrel, as and for the purpose specified.

4. The combination of an intermittently-rotating disk, and a series of rotary mandrels arranged parallel with each other upon said disk, against which said mandrels are successively brought by the rotation of said disk, as and for the purpose specified.

5. The combination of an intermittently-rotating disk, a series of rotary mandrels arranged parallel with each other upon said disk, and a pair of cutters against which said mandrels are successively brought by the rotation of said disk, as and for the purpose specified.

6. The combination of an intermittently-rotating disk, a series of rotary mandrels arranged parallel with each other upon said disk, and a rotary cutter to which said mandrels are successively presented by the rotation of said disk, as and for the purpose specified.

7. The combination of an intermittently-rotating disk, a series of rotary mandrels arranged parallel with each other upon said disk, and a pair of rotary cutters to which said mandrels are successively presented by the rota-

tion of said disk, as and for the purpose specified.

8. The combination of an intermittently-rotating disk, rotary mandrels journaled therein, and a stripper arranged to strip said mandrels, as and for the purpose specified.

9. The combination of an intermittently-rotating disk, a series of rotary mandrels journaled therein, a trimming device, a burnishing device, and a stripper, to which trimming and burnishing devices and stripper said mandrels are successively presented by the rotation of said disk, as and for the purpose specified.

10. The combination of the slide, the feed-trough supported thereby, a rotary cutter, the stripper supported on said slide, an intermittently-rotating disk, and mandrels journaled in said disk, said disk being arranged, when at rest, to present one of said mandrels to the action of said feed-trough, another to the action of said cutter, and a third to the action of said stripper, as and for the purpose specified.

11. The combination of the rotating mandrel, a rotary cutter, and a stripper, as and for the purpose specified.

12. The combination of the feed-trough, rotating mandrel, a rotary cutter, and a stripper, as and for the purpose specified.

In witness whereof I have signed this specification, in the presence of two attesting witnesses, this 23d day of August, A. D. 1889.

JOHN C. CORAM.
